**CENTRIFUGAL SPACE DYEING MACHINE
AND METHOD**

Henry Grady Miller, Jr., Hickory, N.C., assignor to Hickory Dyeing & Winding Co., Inc., Hickory, N.C., a corporation of North Carolina

Continuation of abandoned application Serial No. 373,263, August 10, 1953. This application August 4, 1954, Serial No. 447,765

24 Claims. (Cl. 8—155.1)

This invention relates to a method and means for spot dyeing or space dyeing yarn and more specifically to an improved centrifugally operable machine and method for space dyeing skeins of yarn wherein evenly disposed areas are dyed in the yarn and no blank areas are formed therein.

Heretofore in dyeing of yarn in spots, which is commonly known as space dyeing, wherein one portion of the yarn is dyed one color and other portions of the yarn are dyed other colors, it has been necessary to clamp the yarns between members to divide the skeins of yarn into a plurality of sections and then dyestuff was applied to one or more of said sections as desired to dye only a desired section, the clamps serving to prevent the dyestuff from dyeing the other sections of the yarn. In these prior processes the clamps have covered a portion of the yarn which required that the yarn be again moved in such a manner as to admit dyestuff to that area of the yarn which was covered by the clamps or in the case of yarn wherein the clamps were of relatively narrow width, small undyed areas would appear between the adjacent dyed sections.

It is therefore the primary object of this invention to provide an improved and novel method and means for space dyeing skeins of yarn or the like wherein different areas of the yarn may be dyed different colors which areas will join to each other without overlapping and without leaving any undyed area therebetween.

It is another object of this invention to provide centrifugally operable means wherein means are provided for supporting a plurality of skeins of yarn and additional means are provided for directing different colored dyestuffs to different areas of said yarns and wherein both of said last-named means are rotated so that the dyestuff will flow outwardly and be sprayed onto the yarns and will be caused to thoroughly penetrate the same and to be thoroughly dispersed by the centrifugal movement of the entire apparatus rotating during the dyeing operation.

It is another object of this invention to provide means for space dyeing a plurality of skeins of yarn or the like wherein a rotatable base is provided with a plurality of upstanding vanes adapted to have skeins of yarn looped thereabout and wherein said vanes are adjustable to hold said yarn thereabout. No clamps are provided so that the yarn is not clamped intermediate its ends, thus permitting thorough penetration of the dyestuff to all areas of the yarn. The vanes serve to divide the innermost areas of the yarn into a plurality of designated areas and means are provided for spraying dyestuff between said vanes so as to spray only the area defined therebetween. This entire mechanism is rotated so that the dyestuff will flow outwardly and give thorough penetration and will not mingle with the dyestuff from adjacent areas and at the same time will not leave blank spaces between the dyed areas of the yarn.

It is another object of this invention to provide a centrifugal space dyeing machine of the type described wherein novel means are provided for directing various

2

colored dyestuffs to various areas of the centrifugally operated means for supporting skeins of yarn. Such means include a reservoir disposed above the yarn support means and mounted for rotation therewith, said reservoir being divided into a plurality of compartments each having an electrically operable discharge valve port associated therewith with a plurality of lines leading therefrom to the particular sections of the yarn supporting means. Means are provided for operating one or more of said discharge ports, as desired, to permit dyestuff from one or more of said compartments in said dye reservoir to be sprayed against a designated area of the yarn skeins.

It is another object of this invention to provide a method of space dyeing or of liquid treatment of skeins of yarn wherein the yarn is held taut and divided into a plurality of areas and liquids of different characters are sprayed into said areas while rotating the yarn and spraying apparatus at relatively high speeds whereby centrifugal force will cause thorough penetration of the yarns by the liquids.

This application is a continuation of my copending application Serial No. 373,263, filed August 10, 1953, entitled Centrifugal Space Dyeing Machine and Method, now abandoned.

Some of the objects of the invention having been stated, other objects will appear as the description proceeds, when taken in connection with the accompanying drawings in which—

Figure 1 is a front elevation of the dyeing machine with the parts thereof in dyeing position;

Figure 2 is a side view with parts in section taken along the line 2—2 in Figure 1 and showing the cover of the machine raised prior to commencing a dyeing operation;

Figure 3 is an enlarged sectional plan view of the counterweight and carriage therefor taken along the line 3—3 in Figure 2;

Figure 4 is a sectional plan view of the machine looking substantially along the line 4—4 in Figure 2, but showing the shield and associated parts in lowered position;

Figure 5 is a sectional plan view looking along the line 5—5 in Figure 2 and showing the driving means for the machine;

Figure 6 is an enlarged sectional plan view looking down on the top of the dye reservoir along the line 6—6 in Figure 1;

Figure 7 is an enlarged sectional plan view showing the top of the shield and taken along the line 7—7 in Figure 1;

Figure 8 is an enlarged vertical sectional view through the dye reservoir and shield taken substantially along the line 8—8 in Figure 6 and omitting the flexible dye tubes for purposes of clarity;

Figure 9 is an enlarged fragmentary view of one portion of the shield taken along the line 9—9 in Figure 7;

Figure 10 is an enlarged sectional detail of the upper bearing means taken along the line 10—10 in Figure 1;

Figure 11 is an enlarged sectional plan view taken along the line 11—11 in Figure 10;

Figure 12 is an enlarged view of the central portion of Figure 1 showing the flexible tubes connecting the discharge ports of the dye reservoir to the dye pipes or spray nozzles associated with the shield;

Figure 13 is an enlarged sectional view through the solenoid valve of the dye port taken along the line 13—13 in Figure 6;

Figure 14 is an enlarged sectional plan view looking down along the line 14—14 in Figure 1 and showing the manner in which the pipes or spray nozzles are disposed between the vanes during operation;

Figure 15 is an enlarged sectional plan view taken

along the line 15—15 in Figure 2 and illustrating the manner in which yarn is positioned around the vanes prior to dyeing thereof;

Figure 16 is a vertical sectional view taken along the line 16—16 in Figure 15 and showing the manner in which the yarn supporting vanes are maintained in position;

Figure 17 (Sheet 3) is an enlarged sectional plan view taken along the line 17—17 in Figure 1.

Referring generally to the drawings it will be observed that the invention includes a frame broadly designated at 10 which carries a dye receptacle 11 which surrounds the lower portion of means for supporting a plurality of skeins of yarn such as a table 12 (Figure 16) and a plurality of vanes 13 carried thereby about which the skeins of yarn are adapted to be positioned. The invention also includes a dye reservoir 14 divided into a plurality of compartments for containing dye liquor and a shield or cover 15 adapted to surround the skeins of yarn around the vanes 13 and in which suitable nozzle means are positioned, which nozzles are connected to the dye reservoir 14 for directing predetermined dyestuffs from the dye reservoir 14 to the yarns or skeins around the vanes 13. Means are provided for raising and lowering the dye reservoir 14 and the shield 15 relative to the yarn supporting means 12 and 13 and means are provided for rotating the yarn supporting means 12 and 13 together with the shield 15 and the dye reservoir 14 so that centrifugal force will cause the dyestuff from the nozzles to thoroughly penetrate designated areas of the yarn, which areas are defined by the vanes 13.

Referring more specifically to the drawings, it will be observed that the frame or supporting structure 10 includes front and rear base members 20 and 21 connected by side base members 22 and 23 there also being provided intermediate side frame members 24 and 25 which extend from the front frame member 20 beyond the rear frame member 21 so that the base of the frame 10 is substantially T-shaped. The rear ends of the frame members 24 and 25 are connected by a member 26. Front and rear corner posts 30, 31 and 32, 33 extend upwardly from the ends of the respective base members 20 and 21 and are suitably connected at their upper ends by front and rear members 34 and 35 and side members 36 and 37, so that the foremost portion of the frame 10 is substantially rectangular. Extending from the upper rearmost portion of the frame 10 downwardly to the rearmost portions of the members 24 and 25 are frame members 40 and 41 which serve as a support for the rear portion of the frame and as a guide for counterweight means to be described.

Front and rear lower intermediate support bars 43 and 44 (Figures 1 and 2) extend between the corner posts 30, 31 and 32, 33 in superposed parallel relation to the base frame members 20 and 21. A second front intermediate support member 45 extends between the posts 30 and 31 above the support member 43. Suitable bearings 46 and 47 are suitably secured, as by bolts, to the support members 43 and 45, respectively, and a dye table shaft 48 is rotatably mounted in said bearings and the lower end of the shaft 48 is rotatably mounted in a thrust bearing 49 carried by a bracket 49a secured to the base frame member 20. The shaft 48 extends upwardly and loosely penetrates the bottom of the dye receptacle 11 and has the dye table 12 suitably secured thereto. It will be observed in Figure 16 that the dye table 12 is circular in plan and is provided with a hub portion 50 secured to the shaft 48 as by a set screw 51. The centermost portion of the dye receptacle 11 has a suitable opening therein surrounded by an annular shield 52, which opening is penetrated by the shaft 48.

The dye table 12 forms a part of the means for supporting a plurality of skeins or loops of yarn or the like to be dyed. Said yarn supporting means also includes a plurality of vanes 13 and it will be observed that the dye

table 12 is provided with a plurality of circularly spaced, radially extending slots 53 in which the lowermost ends of the vanes 13 are adapted to be positioned, each of the slots 53 being slightly larger than the base of the vanes 13 to permit the vanes 13 to be tilted slightly therein. The uppermost portion of the inner edge of each of the vanes 13 is cut away in a taper as at 55 to form a cone-like cavity in the center upper portion of the circularly arranged vanes. The upper end of the shaft 48 is threaded for reception of a nut 56 which bears against a round plate 57 having a periphery which fits in the conical cavity formed by the tapered inner edges of the vanes 13 and when pressed downwardly urges the upper ends of the vanes 13 outwardly in a radial direction from the shaft 48. The plate 57 is normally urged upwardly by a coil spring 60 bearing against a hub portion 59 on the lower surface of the plate 57, which coil spring 60 also bears against an intermediate fixed plate 61 suitably secured to the shaft 48 as by set screw 62 and which plate 61 is provided with a plurality of circularly spaced, radially extending slots 63, which slots are in alignment with the slots 53 and are slidably penetrated by the vanes 13. The plate 61 serves as an additional spacer plate to maintain the vanes 13 in the desired circularly spaced relation.

The vanes 13 serve a double purpose in providing means about which a plurality of skeins or loops of yarn may be disposed and in also providing deflector plate means so that dyestuff introduced between two of said vanes will contact only that portion of the yarn positioned between said vanes and will not flow onto other portions of the yarn. This permits the space or spot dyeing of the yarns arranged around the vanes in such a manner as to leave no blank spaces in the yarn and to prevent bleeding of one color dyestuff from one area into another area of the yarn. Some of the vanes 13 are provided with projections 13a to support the lowermost skeins of yarn.

In general operation, the nut 56 and plate 57 may be moved upwardly to permit the upper ends of the vanes 13 to be moved slightly inwardly which facilitates the positioning of a plurality of skeins of yarn indicated at Y around the outer edges of the vanes 13 and then the nut 56 may be tightened against the plate 57 to urge the uppermost outer edges of the vanes 13 outwardly to securely hold the yarns Y in position. The yarns may be stretched if desired or merely held taut by the vanes 13.

It may be desirable in some instances to provide additional yarn holding means such as a plurality of circular bands 65 which may be loosely fitted over the outer surfaces of the yarns Y and if desired spring clip members 66 having U-shaped spring clip elements 67 at their upper and lower ends may be clipped onto a plurality of the vanes 13 so as to extend around the outer surfaces of the bands 65 for additionally holding the yarns against displacement. It should be noted however that in no instance are the yarns Y clamped at any point but they fit snugly against the outer edges of the vanes 13 and may be additionally held in position by the bands 65 and the clips 66, if desired.

The dye receptacle 11 is provided with suitable drainage means such as a valve shown in the form of a faucet 70 for withdrawing used dyestuff from the bottom of the receptacle after the yarns Y have been spot or space dyed in accordance with this invention.

Heretofore in space dyeing yarns it has been necessary to clamp the yarns intermediate their ends in order to prevent dyes in one area from bleeding onto an adjacent area but according to the present invention means are provided for rotating the yarn table 12 together with the vanes 13 thereon so that centrifugal force will cause dyestuffs sprayed against the inner side of the yarns Y between the vanes 13 to move outwardly to completely saturate the yarn Y and wherein the action of said centrifugal force will prevent lateral or circumferential move-

ment of the dyestuffs into adjacent areas so that there will be a clean line of demarcation between each adjacent color. Thus the clamping of the yarns is eliminated and no blank spaces are left in the dyed yarns and there is no bleeding of one color to another color.

Means for rotating the dye table 12 and associated parts are provided comprising a sprocket wheel 70 suitably secured to the shaft 48 and about which a sprocket chain 71 extends. The chain 71 extends around a sprocket wheel 72 fixedly secured on a shaft 73 rotatably mounted in a plurality of bearings 74, 75 and 76 suitably secured to the frame member 44, an intermediate rear frame member 77 and an upper frame member 78, respectively. Suitable means such as collars 79 prevent vertical movement of the shaft 73. The lowermost end of the shaft 73 has a pulley 80 fixed thereon about which a V-belt 81 extends, which belt 81 also extends around a pulley 82 mounted on the drive shaft of a suitable motor 83 from which wires 84 and 85 extend to a master switch connected to a source of electrical energy, not shown. The motor 83 is suitably mounted on a motor bracket 86 extending upwardly from the base frame members 24 and 25.

Now, in order to provide means for introducing dyestuff to the yarns Y between the vanes 13 while the vanes 13 are being rotated there is provided an upper shaft 90 which may be termed a dye reservoir rotating shaft and which is rotatably and slidably mounted in a sleeve 92 (Figure 10) which is fixed in suitable brackets 93 and 94, respectively, connected to the upper frame member 34 and an additional upper frame member 95 disposed therebeneath.

The dye reservoir 14 (Figures 6 and 8) is generally tubular and is provided with a bottom 100 and top 101. The bottom 100 has a bore therein in which one end of a sleeve 102 is sealed and the sleeve 102 extends upwardly slightly above the top 101 through an enlarged opening 103 in the top 101. The sleeve 102 is secured to the shaft 90 by any suitable means such as a set screw 104. The reservoir 14 is divided into a plurality of compartments 106 by means of a plurality of vertically disposed radially extending plates 107 which are secured at their outer surfaces to the tubular wall of the reservoir 14 and are secured at their inner surfaces to the sleeve 102. It will thus be observed that dyestuff may be introduced through the opening 103 into any one of the compartments 106 as desired. For example various colors can be put in the various compartments to thus dye the skeins of yarn Y various colors in various areas.

Now in order to permit the dyestuff to flow from a particular compartment 106 to a particular area of the yarns Y suitable valves broadly designated at 110 are provided adjacent each of the compartments 106 in the reservoir 14. By referring to Figures 12 and 13 it will be observed that a line 111 leads from the lower end of each compartment 106 to the respective valve 110 which valve is preferably an electrically operable solenoid type of valve including a movable valve gate 112, a coil 113 and spring means 114 normally urging the valve gate 112 to closed position.

The valve is shown more or less schematically in Figure 13 and it will be observed that it also includes a discharge stem 115 which is threadably secured to the valve 110 and is closed at its opposite end and is provided with a plurality of discharge ports 116, to which a plurality of tubular stems 117 are suitably secured. A plurality of flexible tubes 118 are fitted on the stems 117 and extend downwardly and are suitably secured to the upper ends of spray nozzles 120 which are circularly arranged in a top plate 121 (Figure 8) of the shield 15. The nozzles 120 are elongated tubular members which are threaded at their upper ends (Figure 9) and penetrate suitable circularly spaced bores in the plate 121 and are secured into position as by lock nuts 122 and 123. The lower end of each nozzle 120 is closed and the outer sur-

face of each nozzle is provided with a plurality of spaced discharge ports or spray jets 125, it being observed that the uppermost opening or jet 125 is the largest and the diameter of the jets 125 progressively decreases from top to bottom of the nozzle 120. Since the dyestuff sprayed from the nozzles tends to flow downwardly this arrangement of the bores 125 permits even distribution of the dyestuff on the yarns.

The nozzles 120 are so spaced in the plate 121 as to fit down beneath each of the vanes 13 when the nozzles are lowered into dyeing position and it will thus be observed, referring to Figure 14, that dyestuff emitted from the nozzles 120 will be sprayed outwardly adjacent the inner surfaces of yarn extending around the vanes 13 and the vanes 13 will serve to deflect the dyestuff so that it will be sprayed only on that area of the yarn which is between the particular vanes 13. It is desirable to have the yarns dry and to apply dye to all areas of the yarn simultaneously to prevent bleeding. There may be a very small amount of bleeding of the dyes on each side of the vanes but this will be limited by centrifugal force so as to bleed only a distance approximately one-half of the thickness of the vane 13 so that it will meet with the adjacent dyestuff and there will be a definite clear line of demarcation between the dyed areas without any blank space whatsoever therebetween due to the fact that the yarns are not clamped against the outer edges of the vanes 13.

When it is desired to leave one or more areas blank, one or more of the compartments 106 of the dye reservoir is filled with water and water is sprayed onto the yarns between certain designated vanes at the same time dye is sprayed onto the other areas. This keeps the dye from other areas from bleeding into the water saturated areas and any dye that might bleed into said areas due to difference in the densities of water and dye would readily wash out in the finishing process.

The upper or top plate 121 of the shield 15 (Figure 8) is fixed on the lower threaded end of the shaft 90 as by lock nuts 130 and 131 and it will be observed that the dye reservoir 14 is additionally supported by the plate 121 by means of a plurality of strap support members 132 suitably secured, as by welding, to the bottom 100 of the reservoir 14 and to the upper surface of the plate 121. A lock nut 133 also serves to secure the dye reservoir 14 in position about the shaft 90. A suitable handle or ring 135 extends around and is connected to the shield 15, which shield is generally tubular and tapers outwardly from top to bottom and the handle member 135 serves as grasping means for raising the shield 15 and associated parts.

Means are provided for rotating the shaft 90 in unison with the shaft 48 comprising a sprocket wheel 140 provided with a hub portion 141 having an annular groove 142 therein which is rotatable in a U-shaped slot 143 (Figures 1 and 10) in a plate 144 suitably secured as by screws 146 to a bracket 145 secured to and extending downwardly from the frame members 34 and 95. The hub 141 of the sprocket 140 is secured for rotation with the shaft 90 by means of a recessed set screw 147 which penetrates a key 149 positioned in an elongated keyway 150 in the shaft 90 which permits the shaft 90 to move vertically relative to the sprocket wheel 140 but causes the shaft 90 to rotate with the sprocket wheel 140, the plate 144 serving also to prevent vertical movement of the sprocket 140. A sprocket chain 151 extends around the sprocket wheel 140 and around a sprocket wheel 152 suitably secured to the shaft 73 adjacent its upper end. The shaft 73 also drives the sprocket 70 for rotating the shaft 48 and it will thus be observed that like rotation will be imparted to the shaft 90.

Suitable means are provided for transmitting electrical energy from a stationary source to the rotating solenoid valves 110 associated with each of the compartments 106 of the dye reservoir 14 and in the present instance said means are illustrated in Figures 10 and 11 as comprising

an insulated ring 160 suitably secured to the key 149 as by a set screw 161, the keyway 150 in the shaft 90, to permit the shaft 90 to move vertically without moving the insulated ring 160. The set screw 161 in the ring 160 is recessed and a conductive ring 162 extends around the insulated ring 160 out of contact with the set screw 161 and this conductive ring 162 may be secured to the insulated ring 160 by means of a recessed or flush set screw 163 which does not extend all the way through the ring 160. A stationary housing 165 is suitably mounted on a bracket 165a depending from the frame member 95 and the housing 165 is provided with an insulating ring 166 fixed therein spaced from the conductive ring 162 and a conductive pin or brush 177 is mounted in the ring 166 and contacts the conductive ring 162. Suitable wires 178 and 179 lead from the brush 177 through a duct 180 in the housing 165. These wires 178 and 179 extend outwardly to the frame 10 and are suitably connected to a switch 182 (Figure 1) which is provided with wires 183 and 184 which lead to a suitable source of electrical energy not shown.

It will thus be seen as the shaft 90 rotates electrical energy will be transmitted through the brush 177 to the ring 162 and the ring 162 has suitable wires 185 connected thereto which extend downwardly through the opening in the housing 165 and are connected by means of circular wires 186 and branch wires 187 to each of the solenoid switches 110. Thus by operation of the switch 182, a circuit may be made to the solenoid switches 110. If desired a suitable control unit may be placed in the circuit so as to permit individual operation of designated solenoid valves but in general operation this is not necessary as all portions of the yarn are usually dyed and it is thus desirable to operate all the solenoid valves 110 at the same time.

In order to raise the dye reservoir 14 and the shield 15 to permit the placement and removal of the yarns Y about the vanes 13, the upper end of the shaft 90 has secured thereto the inner race of a ball bearing disposed in a bracket 200. The bracket 200 has one end of a sprocket chain 201 secured thereto which chain 201 extends upwardly and over a sprocket wheel 202 suitably journaled in the upper parallel ends of upper frame members 203 and 204 which are mounted on and extend upwardly and inwardly toward each other from the opposite ends of the upper frame member 34. The sprocket chain 201 then extends downwardly over a sprocket wheel 205 suitably journaled between intermediate frame members 206 and 207 on top of the frame 10.

The chain 205 extends downwardly and is connected at its lower end to a projecting lug 210 (Figure 3) extending from the uppermost surface of a generally inverted U-shaped weight plate 211 which is slidably mounted on the diagonally extending frame member 40 and 41, it being observed that the frame members 40 and 41 are U-shaped in cross-section and are provided with ribs 212 on their upper surfaces which act as bearings for the plate 211. The plate 211 is provided with side walls 215 and 216 and an end wall 217. A suitable strap 218 extends from the side wall 215 and to side wall 216 and serves to confine suitable weight members W on the plate 211. The weight members W are counterweights and serve to counterbalance the weight of the shield 15, the dye reservoir 14 and associated parts.

Thus upon an operator grasping the handle 135 and moving the shield 15 and dye reservoir 14 upwardly the weights W carried by the basket formed of the plate 211 and associated parts moves downwardly on the frame members 40 and 41 to hold the dye reservoir 14 and shield 15 in any desired raised, partially raised, or lowered position. A suitable stop 219 projecting from a bar 219a extending between the members 24 and 25 limits movement of the counterweight beyond a predetermined point. Any suitable counterweight means may be pro-

vided and the means shown are by way of illustration only.

5 The bracket or bearing housing 200 has an arm 220 extending therefrom between suitable guide members 221 and 222 extending upwardly from the members 206 and 207 and supported by brace bars 223 and 224 also secured to the members 206 and 207. The arm 220 prevents rotation of the bracket 200 with the shaft 90.

In operation the shield 15 and associated parts are 10 moved to the position shown in Figure 2 and a plurality of skeins of yarn Y are positioned about the vanes 13 and the vanes 13 are tightened into position by means of the nut 56 and the plate 57 as previously described. If desired the additional yarn holding means such as the bands 65 15 may be utilized. The compartments 106 of the dye reservoir 14 are then filled with any suitable colored dyestuffs. If desired, as many as eight different colored dyes may be used in the present illustration and it may be desirable in some instances to provide a dye reservoir containing a 20 greater or smaller number of compartments.

In the present illustration five discharge ports are shown 25 leading from each of the compartments 106 and by arranging the flexible tubes 118 in a desired arrangement, the dyestuff may be utilized so that any desired color dyestuff 30 may be introduced to yarn in the area between any two adjacent vanes. In this connection it should be noted that in some instances it may be desirable to use flexible tubes substantially longer than those shown at 118 in order to give maximum flexibility and variety to this 35 apparatus.

After the tubes 118 have been arranged as desired and the reservoir 14 is filled with dyestuff the shield 15 and associated parts are manually lowered so that the lower edges of the shield 15 fit within the uppermost edge of the 40 dye receptacle 11 (Figure 16). The mechanism is then caused to rotate by actuation of the motor 83 and which actuation is preferably controlled by means of a master switch 250 (Figure 1) having wires 251 and 252 leading to a suitable source of electrical energy and also being connected to the wires 84 and 85 of the motor 83.

Upon the dye table 12 and the vanes 13 and associated 45 parts rotating together with the shield 15 and the reservoir 14, the switch 182 may be actuated to open the valves 110 to permit the flow of dyestuff from the dye compartments 106 through the valves 110 the flexible tubes 108 and to the discharge nozzles 120 from which the dyestuff will be sprayed through the discharge openings, sprays or jets 125 against the innermost surfaces of the yarns Y positioned around the vanes 13. Due to the fact that the 50 entire mechanism is rotating during this operation centrifugal force will cause the dyestuff to flow outwardly to thoroughly penetrate each of the yarns Y while at the same time preventing sidewise or circumferential movement of the dyestuff to prevent bleeding of one color into 55 the color of another adjacent area. The dyestuff will then flow downwardly and be retained in the receptacle 11 and may be discharged by the valve 70 if desired. It will be observed that the flange 52 in the bottom of the receptacle 11 prevents leakage and if desired any suitable rotary 60 connection or packing may be provided at this point to further prevent leakage.

The speed of rotation of the dyeing mechanism may 65 vary in accordance with varying factors such as the size of the machine, the size of the motor 83, the particular type and quantity of yarn being processed, the particular type of fluid or dyestuff used, the amount of penetration desired and various other factors. In actual operation it has been found that a speed of rotation of the shafts 48 and 90 of from 180 to 240 revolutions per minute gave 70 desired results. In the particular machine utilized good results were obtained with a speed of 200 revolutions per minute. This gives sufficient penetration of the yarns and extraction of the excess dyestuffs. It is believed that high speed is limited only by the structural characteristics of 75 a particular machine but low speed of about 180 revolu-

tions per minute appears to be necessary to give the desired results.

The used dyestuff may be drawn off and the alcohol salvaged therefrom, if desired. In some instances, it may be desirable to construct the receptacle 11 so as to cause the same to rotate with the shaft 48 and to divide the receptacle 11 into a plurality of compartments so as to salvage the dyestuff without an intermingling of colors but in ordinary usage it is found more economical to construct the receptacle as shown as only the alcohol or other chemical carrier of the dyestuff is normally subject to salvage and reuse and an intermixing of the used dyes generally is not critical.

After the desired amount of dye has been sprayed on the yarns Y, rotation of the unit may be stopped by means of the master switch 250 and the shield 15 and associated parts may be raised to the position shown in Figure 2 to permit the yarns Y to be removed from the vanes 13.

It will thus be observed that there is provided a new type of space dyeing machine and method wherein centrifugal force is utilized to cause the dyes to flow outwardly through a predetermined area of yarn and to prevent intermingling of various colored dyes in various sections of the yarn being dyed. Such means and method eliminates the necessity of clamping the yarn which either leaves blank spaces in the yarn requiring subsequent dyeing or which permits intermingling of the dyes and bleeding of the dyes of one color to colored areas adjacent thereto. The use of centrifugal force also gives more thorough penetration of the dyestuff and results in spaced dyed yarns of much higher quality than have heretofore been obtainable by the use of prior apparatus.

In the drawings and specification there has been set forth a preferred embodiment of the invention and although specific terms are employed, they are used in a generic and descriptive sense only, and not for purposes of limitation, the scope of the invention being defined in the claims.

I claim:

1. That method of liquid treatment of yarns comprising the steps of assembling lengths of yarn about a vertical support in superposed taut relation, dividing the inner surface of said yarns into a plurality of areas shielded from each other, applying liquids of different character to the inner shielded areas of said yarns and simultaneously rotating the yarns and the support at a speed of at least 180 revolutions per minute while applying said liquids whereby centrifugal force will cause thorough penetration of the yarns by the liquids.

2. That method of treating yarns which comprises positioning a plurality of superposed yarns around a central support, dividing the inner surfaces of said yarns into a plurality of areas shielded from each other, applying liquids of different character to the inner surfaces of the yarns in each shielded area and simultaneously rotating said yarns and said support while applying said liquids, the speed of rotation being such that centrifugal force will cause thorough penetration of the yarns by the liquid.

3. That method of treating yarns in skein form which comprises positioning a plurality of superposed yarn skeins around a central support, exerting radial pressure against said yarns at spaced points to hold the same taut, dividing the inner surfaces of said yarns into a plurality of areas shielded from each other spraying liquids of different character against the inner surfaces of the yarns in each shielded area and simultaneously rotating said yarns and said support while spraying said liquids, the speed of rotation being such that centrifugal force will cause thorough penetration of the yarns by the liquid.

4. That method of liquid treatment of yarns in skein form comprising the steps of assembling skeins of yarn about a vertical support in superposed relation, dividing the inner surfaces of said yarns into a plurality of areas

shielded from each other by a plurality of circularly arranged vanes, exerting radial pressure on said vanes to cause their outer edges to contact said yarns to hold the same taut, spraying liquids of different characters 5 simultaneously on the inner shielded areas of said yarns and simultaneously rotating the yarns and the support at a speed of at least 180 revolutions per minute while spraying said liquids whereby centrifugal force will cause thorough penetration of the yarn by the liquids.

10. Apparatus for the liquid treatment of yarns comprising a support rotatable about an axis, a plurality of circularly arranged longitudinally-extending yarn holding means mounted on said support for holding a plurality of yarns disposed therearound, a shield for enclosing said yarns, and said yarn holding means, said yarn holding means dividing said yarns into a plurality of areas shielded from each other, means for spraying liquids of different character against the inner surface of said yarns in said shielded areas, and means for rotating said yarn support and spraying means simultaneously whereby centrifugal force will cause said liquids to thoroughly penetrate the adjacent areas of said yarn.

6. Apparatus for space dyeing yarn skeins comprising a rotatable support, a plurality of radially movable circularly arranged yarn holding means mounted on said support for holding a plurality of yarn skeins disposed tautly therearound, a movable shield for enclosing said yarns and said yarn holding means, said yarn holding means dividing said yarns into a plurality of areas 25 shielded from each other, means for spraying liquids of different character against the inner surface of said yarns in each of said shielded areas, and means for rotating said yarn support and spraying means simultaneously at a relatively high speed whereby centrifugal force 30 will cause said liquids to thoroughly penetrate the adjacent areas of said yarns.

7. Apparatus for space dyeing yarn skeins comprising a rotatable support, a plurality of radially movable circularly arranged yarn holding vanes mounted on said support for holding a plurality of yarn skeins disposed tautly therearound, a movable cover for enclosing said yarns and said yarn holding vanes, said yarn holding vanes engaging the yarns at spaced points and dividing said yarns into a plurality of areas shielded from each other, a plurality of spray nozzles carried by said cover and extending between each of said vanes when said cover is in closed position, means for spraying liquids of different character from said nozzles against the inner surface of said yarns in each of said shielded areas, and means for rotating said yarn support and spraying means simultaneously at a speed of at least 180 revolutions per minute whereby centrifugal force will cause said liquids to thoroughly penetrate the adjacent areas of said yarns.

8. Apparatus for space dyeing yarn skeins comprising a support rotatable about a vertical axis, a plurality of radially movable circularly arranged vertical yarn holding vanes mounted on said support for holding a plurality of yarn skeins disposed tautly therearound, a vertically movable cover for enclosing said yarns and said yarn holding vanes, said yarn holding vanes engaging the yarns at spaced points and dividing said yarns into a plurality of areas shielded from each other, means for spraying liquids of different characters against the inner surface of said yarns in said shielded areas, a receptacle positioned beneath said support for receiving excess liquid sprayed onto said yarns, and means for rotating said yarn support and spraying means simultaneously at a speed of at least 180 revolutions per minute whereby centrifugal force will cause said liquids to thoroughly penetrate the adjacent areas of said yarns.

9. Apparatus for space dyeing a plurality of skeins of yarn comprising a rotatable table, a plurality of vanes movably mounted on said table and adapted to have a plurality of yarns positioned therearound said vanes

being radially movable to hold said yarns in taut position and said vanes also serving to define a plurality of areas on the inner surfaces of said yarns shielded from each other, movable cover means adapted to enclose said yarns and said vanes, a liquid reservoir movable with said cover means, said liquid reservoir having a plurality of compartments therein, a plurality of spray nozzles carried by said cover means, means leading from the compartments of said liquid reservoir to each of said spray nozzles for directing liquid thereto, said spray nozzles being so arranged as to fit between each of said vanes and to direct liquid therefrom against the inner surfaces of said yarns disposed between said vanes, and means for simultaneously rotating said table and vanes and said cover and spray means during the dyeing operation.

10. Apparatus for space dyeing a plurality of skeins of yarn comprising a rotatable table, a plurality of vanes mounted on said table and adapted to have a plurality of yarns spaced therearound in adjacent taut relation to each other, said vanes engaging said yarns at spaced points and said vanes defining a plurality of areas on the inner surfaces of said yarns shielded from each other by said vanes, movable cover means adapted to enclose said yarns and said vanes, a dye reservoir movable with said cover means, said dye reservoir having a plurality of compartments therein, a plurality of elongated spray nozzles carried by said cover means, conduits leading from the compartments of said dye reservoir to each of said spray nozzles for directing dyestuff thereto, and said nozzles being so arranged as to fit between each of said vanes and having discharge ports therein to direct dyestuff therefrom against the inner surfaces of said yarns disposed between said vanes, and means for simultaneously rotating said table and vanes, said cover means and said dye reservoir during the dyeing operation.

11. Apparatus for space dyeing a plurality of skeins of yarn comprising a table rotatable about a vertical axis, a plurality of vertically disposed circularly spaced vanes mounted on said table and adapted to have a plurality of yarns spaced therearound in contiguous relation to each other, said vanes being radially movable to hold said yarns in taut condition, said vanes engaging the yarns at spaced points and defining a plurality of shielded areas on the inner surfaces of said yarns, cover means for enclosing said yarns and said vanes, a liquid reservoir, said liquid reservoir having a plurality of compartments therein, a plurality of spray nozzles carried by said cover means, means leading from the compartments of said liquid reservoir to each of said spray nozzles for directing liquids thereto, said nozzles being so arranged as to fit between each of said vanes and to direct liquid against the inner surfaces of said yarns disposed between said vanes, means for rotating said table and vanes, and means for rotating said cover and said liquid reservoir simultaneously with the rotation of said table and vanes.

12. Apparatus for space dyeing a plurality of skeins of yarn comprising a table rotatable about a vertical axis a plurality of vertically disposed circularly spaced vanes mounted on said table and adapted to have a plurality of yarns, spaced therearound in contiguous relation to each other, said vanes being radially movable to hold said yarns in taut condition, said vanes engaging the yarns at spaced points and defining a plurality of shielded areas on the inner surfaces of said yarns, cover means for enclosing said yarns and said vanes, a liquid reservoir, said liquid reservoir having a plurality of compartments therein, a plurality of spray nozzles carried by said cover means, means leading from the compartments of said liquid reservoir to each of said spray nozzles for directing liquids thereto, said nozzles being so arranged as to fit between each of said vanes and to direct liquid against the inner surfaces of said yarns disposed between said vanes, means for simultaneously rotating said table, vanes, cover, and liquid reservoir, and a receptacle positioned

beneath said table and said cover for reception of excess liquid sprayed on said yarns.

13. Apparatus for space dyeing a plurality of skeins of yarn comprising a rotatable table, a plurality of circularly arranged vanes mounted on said table and adapted to have a plurality of yarn skeins positioned therearound, said vanes being radially movable to hold said yarns in taut condition; said vanes engaging said yarns at spaced points and defining a plurality of shielded areas on the inner surfaces of said yarns, movable cover means adapted to enclose said yarns and said vanes, a dye reservoir movable with said cover means, said dye reservoir having a plurality of compartments therein, a plurality of spray nozzles carried by said cover means, an electrically operable valve connected to each of said compartments in said dye reservoir, each of said valves having a plurality of discharge ports, conduits connecting each of said discharge ports to one of the spray nozzles, means for simultaneously opening all of said 20 electrically operable valves, said nozzles being so arranged as to fit between each of said vanes and to direct liquid therefrom against the inner surfaces of said yarns disposed between said vanes, and means for simultaneously rotating said table and vanes and said cover means during the dyeing operation.

14. Apparatus for the liquid treatment of a plurality of skeins of yarn comprising a means for holding a plurality of skeins of yarn in taut contiguous relation, said means also defining a plurality of areas on the inner surfaces of said yarns shielded from each other, movable cover means adapted to enclose said yarns and said yarn holding means, a liquid reservoir, said liquid reservoir having a plurality of compartments therein, a plurality of spray nozzles carried by said cover means, means leading from the compartments of said liquid reservoir to each of said spray nozzles for directing liquid thereto, and said spray nozzles being so arranged as to fit adjacent each of the shielded areas of said yarns and to direct liquid therefrom against the inner surfaces of said areas of said yarns, and means for simultaneously rotating said 35 yarn holding means and said cover means and liquid reservoir during the dyeing operation.

15. Apparatus for the liquid treatment of a plurality of skeins of yarn comprising a means for holding a plurality of skeins of yarn in taut contiguous relation, said means also defining a plurality of areas on the inner surfaces of said yarns shielded from each other, movable cover means adapted to enclose said yarns and said yarn holding means, a liquid reservoir, said liquid reservoir having a plurality of compartments therein, a plurality of spray nozzles carried by said cover means, means leading from each of the compartments of said liquid reservoir to its associated nozzles for directing liquid thereto, and said spray nozzles being so arranged as to fit adjacent each of the shielded areas of said yarns and to direct liquid therefrom against the inner surfaces of said areas of said yarns, means for simultaneously rotating said 40 yarn holding means and said cover means and liquid reservoir during the dyeing operation, said means leading from the compartments of the liquid reservoir each including an electrically operable valve having a plurality of discharge ports each operatively connected to a spray nozzle.

16. In a space dyeing apparatus for yarn skeins, means for supporting a set of contiguous skeins and dividing the inner surfaces of said skeins into a plurality of areas and shielding each of said areas from the next adjacent area, a dye reservoir having a plurality of compartments adapted to hold a plurality of different colored dyes, a plurality of nozzles connected to said dye reservoir and positioned between each of said yarn dividing and shielding means and being provided with openings therein directed against the inner surfaces of said yarn skeins, means for moving said nozzles to bring the same into operative position adjacent said yarn skeins, means for

causing liquids within said reservoir to flow therefrom and to be emitted simultaneously from all of said nozzles, and means for rotating all of said above-named apparatus simultaneously during the dyeing operation.

17. In a space dyeing apparatus for yarn skeins, means for supporting a set of contiguous skeins and dividing the inner surfaces of said skeins into a plurality of areas and shielding each of said areas from the next adjacent area, a dye reservoir having a plurality of compartments adapted to hold a plurality of different colored dyes, a plurality of nozzles positioned between each of said yarn dividing and shielding means and being provided with openings therein directed against the inner surfaces of said yarn skeins, valves connected to said dye reservoir, each of said valves having a plurality of discharge ports, conduits connecting each of said discharge ports to one of the spray nozzles, means for operating said valves to cause liquids within said reservoir to flow therefrom and to be emitted simultaneously from all of said nozzles, and means for rotating all of said above-named apparatus simultaneously during the dyeing operation.

18. In a space dyeing apparatus for yarn skeins, means for supporting a set of contiguous skeins, and dividing the inner surfaces of said skeins into a plurality of areas and shielding each of said areas from the next adjacent area, a dye reservoir having a plurality of compartments adapted to hold a plurality of different liquids, a plurality of nozzles connected to said dye reservoir and positioned between each of said yarn dividing and shielding means and being provided with openings therein directed against the inner surfaces of said yarn skeins, means for causing liquid within said reservoir to flow therefrom and to be emitted from said nozzles, means for rotating all of said above-named apparatus simultaneously during the dyeing operation, and means for receiving any excess liquids applied to said yarns.

19. Apparatus for space dyeing yarns comprising a frame, a table rotatably mounted in the lower portion of said frame, a plurality of vertically extending circularly spaced vanes mounted on said table and adapted to have a plurality of skeins of yarn positioned therearound in superposed relation to each other, means for moving said vanes radially to hold said yarns taut, said vanes serving to divide said yarns into a plurality of areas and to shield each of said areas from the next adjacent area, a rotatable and slideable shaft mounted in the upper portion of said frame, a dye reservoir fixed on said shaft to rotate therewith, a cover carried by said dye reservoir and adapted to enclose said yarns and said vanes, a plurality of elongated circularly spaced nozzles carried by said cover and depending therefrom, said dye reservoir being divided into a plurality of compartments for containing liquids of different characters, conduit means leading from each of said compartments to certain of said nozzles, means for controlling the flow of liquids from said compartments to said nozzles, means for moving said shaft vertically to position the cover about said yarns and the nozzles between each of said vanes, said nozzles each having a plurality of ports therein facing toward said yarns, and means for simultaneously rotating said rotatable and slideable shaft and said table during the dyeing operation whereby centrifugal force will cause liquids emitted from said nozzles to thoroughly penetrate said yarns and will prevent bleeding of said liquids from one area to the next adjacent area.

20. Apparatus for space dyeing yarns comprising a frame, a table rotatably mounted in the lower portion of said frame, a plurality of vertically extending circularly spaced vanes mounted on said table and adapted to have a plurality of skeins of yarn positioned therearound in superposed relation to each other, means for moving said vanes radially to hold said yarns taut, said vanes serving to divide said yarns into a plurality of areas and to shield each of said areas from the next adjacent area, a rotatable and slideable shaft mounted in the upper por-

tion of said frame, a dye reservoir connected to said shaft, a cover carried by said dye reservoir and adapted to enclose said yarns and said vanes, a plurality of elongated circularly spaced nozzles carried by said cover and depending therefrom, said dye reservoir being divided into a plurality of compartments for containing liquids of different characters, conduit means leading from each of said compartments to certain of said nozzles, means for controlling the flow of liquid from said compartments to said nozzles, means permitting manual movement of said shaft vertically to position the cover about said yarns and to position the nozzles between each of said vanes, counterweight means connected to said rotatable and slideable shaft to cause the cover and dye reservoir to remain in any desired position, said nozzles each having a plurality of ports therein facing toward said yarns, and means for simultaneously rotating said rotatable and slideable shaft and said table during the dyeing operation whereby centrifugal force will cause said liquids to thoroughly penetrate said yarns and will prevent bleeding of liquids from one area to the next adjacent area.

21. Apparatus for space dyeing yarns comprising a frame, a table rotatably mounted in the lower portion of said frame, a plurality of vertically extending circularly spaced vanes mounted on said table and adapted to have a plurality of skeins of yarn positioned therearound in superposed relation to each other, means for moving said vanes radially to hold said yarns taut, said vanes serving to divide said yarns into a plurality of areas and to shield each of said areas from the next adjacent area, a rotatable and slideable shaft mounted in the upper portion of said frame, a dye reservoir connected to said shaft, a cover carried by said dye reservoir and adapted to enclose said yarns and said vanes, a plurality of elongated circularly spaced nozzles carried by said cover and depending therefrom, said dye reservoir being divided into a plurality of compartments for containing liquids of different character, an electrically operable valve connected to each of said compartments in said dye reservoir, each of said valves having a plurality of discharge ports, conduits connecting each of said discharge ports to one of the spray nozzles, means for controlling said valves to control the flow of liquid from said compartments to said nozzles, means for moving said shaft vertically to position the cover about said yarns and the nozzles between each of said vanes, each of said nozzles having a plurality of ports therein facing toward said yarns, and means for simultaneously rotating said rotatable and slideable shaft and said table during the dyeing operation whereby centrifugal force will cause said liquids emitted from said nozzles to thoroughly penetrate said yarns and will prevent bleeding of said liquids from one area to the next adjacent area.

22. That method of treating fibrous material including the steps of positioning the material about a plurality of circularly arranged vertical supports, dividing the material into a plurality of shielded areas, and spraying liquids of different character against the inner surfaces only of the portions of said material bridging adjacent supports while rotating said supports and said material about a common axis at a speed such as to cause said liquids to penetrate said material by centrifugal force.

23. A method of liquid treatment of yarns comprising the steps of positioning the yarn about a support, holding the yarn about the support in taut relation, dividing the yarn into a plurality of areas shielded from each other, flowing liquid from a position above the yarn into spraying receptacles, and simultaneously rotating the yarn, support, and spraying receptacles whereby centrifugal force will be effective to cause the liquid to be thrown radially outwardly from the spraying receptacles to thoroughly penetrate the yarn.

24. A method of liquid treatment of yarns comprising the steps of holding a plurality of yarn skeins about a

support in taut relation, dividing the yarn skeins into a plurality of areas shielded from each other, flowing treatment liquid from a position above the yarn skeins into spraying receptacles, and simultaneously rotating the yarn, support, and spraying receptacles whereby centrifugal force will be effective to cause the liquid to be thrown radially outwardly from the spraying receptacles to thoroughly penetrate the yarn.
